Inventor

Conrad H. Ahlmansiek.

UNITED STATES PATENT OFFICE.

CONRAD H. OHELMANSIEK, OF DILLSBORO, INDIANA.

AUTOMATIC SPEED-CHANGE DEVICE.

Application filed June 9, 1923. Serial No. 644,356.

This invention relates to an automatic speed change device for changing the speed of the generator drive shaft.

An object of the invention is to provide means whereby a direct drive is accomplished when the battery is fully charged, and to automatically increase the speed of the generator drive shaft when the battery is to be charged.

Another object is the provision of means for increasing the speed of the generator drive shaft when revolving at a low rate of speed, and to form a direct drive when revolving at a high rate of speed.

A still further object is to provide means whereby the speed of a generator drive shaft will be held to the low rate when the battery is fully charged, irrespective of the speed of the driving means.

Other objects and advantages of the invention will be apparent during the course of the following description.

In the accompanying drawings forming a part of this application, and in which like numerals are employed to designate like parts throughout the same;

Figure 1 is a plan view of my improved apparatus.

Figure 2 is a central section taken on line 2-2 of Figure 1.

Figure 3 is a cross section taken on line 3-3 of Figure 2.

Figure 4 is a view partially in section, similar to Fig. 2, showing the apparatus in a different position.

Figure 5 is a side elevation of the automatic operating means.

Figure 6 is a section taken on line 6-6 of Fig. 5.

Figure 7 is a section taken on line 7-7 of Fig. 1.

Figure 8 is a detail view showing the member to be operated by the battery, and

Figure 9 is a diagrammatic view of the means for determining the operation of the device.

In the drawing, the numeral 10 designates a hollow drive shaft mounted loose upon a driven shaft 11, by the means of roller bearings 12 and 13 at the opposite ends of said hollow drive shaft. Permanently secured to one end of said drive shaft

10 is a gear 14 to which the power from an engine or the like is adapted to be applied. Arranged for supporting said shafts are 55 two upright supports 15 and 16 having their upper and lower ends suitably secured to cross braces 17 and 18. Said upright 15 has a roller bearing or the like 19 mounted therein for receiving the hollow sleeve 10, 60 while the upright 16 has a bearing 20 to receive the driven shaft 11.

Secured to said hollow shaft 10 is a clutch member 21 having two enlarged slots 22 cut directly opposite each other in the periphery thereof for receiving the clutch shoes 23 and 24. Said shoes have inwardly extending lugs 25 adapted to slide in grooves 26 for holding said shoes in proper position. The engaging faces of said shoes are 70 arcuately curved as at 27 for engaging the interior face of a drum 28, which is in turn carried by a large gear 29. The gear 29 has a roller 30 mounted therein to form a bearing upon the hollow drive shaft 10. 75

Mounted in the upright supports 15 and 16, above the drive and driven shafts, are bearings 31 and 31' for receiving a counter-shaft 32. Upon one end is secured a small gear 33 which meshes with the large gear 29. At the opposite end of said counter-shaft 32 and adjacent said bearing 31' is secured another gear 34 to mesh with a gear 35 equal in size, secured upon the driven shaft 11. It can be seen that the gear 29 is 85 loose upon the hollow shaft 10, and by means of the clutch 21 it may be secured thereto for driving through the train of gears 29, 33, 34, 35, and thus drive the driven shaft 11 at a greater speed than the hollow drive 90 shaft 10.

For operating the clutch shoes 23 and 24, a large fly wheel 36 is permanently secured upon the hollow drive shaft, having slots 37 and 38 therein for receiving the governor 95 members 39 and 40. Said governor members are T-shaped and have one arm pivoted as at 41 to the fly wheel 36, while another arm extends through the fly wheel and has weighted ends 42 having screw threaded 100 openings therein to receive the threaded bolts 43 to which a coil spring 44 is fastened for holding the weighted ends in. By turning said threaded bolts 43, an adjustment

may be had for the governor. The other arms of the T-members 39 and 40 extend in as at 45 and engage in an annular groove 46 provided in a sleeve 47 slidably mounted upon said hollow drive shaft 10. Extending from said sleeve 47 are arms 48 to which are pivotally connected radiating screw threaded arms 49 threaded in the interior of hollow shaft 50, which in turn are pivotally connected as at 51 to said clutch shoes 23 and 24. From the foregoing it can be seen that when the fly wheel 36 revolves at a high rate of speed the weighted end 42 of the T-shaped governors 39 and 40 will swing out away from each other, causing the arms 45 to slide the sleeve 47 towards the fly wheel 36, and consequently draw the clutch shoes 23 and 24 in and away from the drum 28.

20 Permanently mounted upon the hollow drive shaft 10, between the fly wheel 36 and the gear 35, is a sleeve 52 having a pair of small bores 53 therein parallel with the main central bore and alining with bores 54 in 25 the hub of the fly wheel 36. Said bores 53 receive pins 55 adapted to engage the gear 35 when pressure is applied through the medium of springs 56 being compressed by the 30 slidable sleeve 47 pressing the pins 57 there against. When clutch shoes 23 and 24 disengage the drum 28, the pins 55 will engage the gear 35 and consequently cause a direct drive through the hollow shaft 10.

Upon the sleeve 52 is a worm 58 adapted 35 to mesh with a worm gear 59 upon a shaft 60 carried by a U-shaped supporting frame 61 secured to the uprights 15 and 16. The shaft 60 has a worm 62 thereon which meshes with a worm gear 63 upon the shaft 40 64 mounted in brackets 65. A worm 66 is also provided on the shaft 64 to mesh with a worm gear 67 secured to the shaft 68. Through these worms and worm gears the 45 speed of the shaft 68 is reduced to a low degree compared with the speed of the other mechanism.

The shaft 68 extends across the machine and has a cam or eccentric 69 connected thereto and is supported in the U-shaped 50 supporting frame 70. Slidably mounted by guides 71 on each side of the supporting frame 70, are T-shaped members 72 and 73. The lower arms of the T-members extend down as at 74 and 75 to be engaged by the 55 cam or eccentric 69 to slide the T-members. A spring 76 yieldably connects the downwardly extending arms or legs together so that both will engage the eccentric 69. The T-member 73 has one leg relatively longer 60 than the T-member 72, as at 76', and has at its end a lug 77 adapted to extend through a slot 78 to engage one end of still another T-member 79 slidably supported on the same 65 side of the supporting frame 70 as the T-member 72, in guides 71, while the relatively

short leg 80 of the T-member 72 engages the opposite end of said T member 79, so that the movement of one of the T members 72 or 73 will move the T member 79 in one direction while the other of the T members 72 or 73 will move said T member 79 in the opposite direction. The legs 81 and 82 of the T-members 72 and 73 extend along each side of an extension 83 and have notches 84 and 85 therein to be engaged by a movable 75 member 86 carried by the extension 83 which is controlled by the battery. By the member 86 engaging in either of the notches 84 or 85 of the T-members 72 or 73 the same will be locked against sliding movement, 80 thus the sliding movement of said T member 79 will cease.

The T-member 79 has an arm 87 extending forwardly and engaging an annular groove 88 in a collar 89 slidably mounted upon the sleeve 52. The supporting frame 70 has an upwardly extending portion 90 upon which an arm 91 is pivoted as at 92 and has its opposite end bifurcated as at 93 to engage over the arm 87 of the T-member 79. A 90 spring 94 has one end connected to the arm 91 as at 95, while the other end is connected to the extension 90 as at 96. It can be seen that should neither the leg 81 or 82 of the T-members 72 and 73 be engaged by the member 86 that the T-members 72 and 73 would be slid back and forth by the arms 74 and 75 engaging the eccentric 69, sliding the T-member 79 therewith and consequently the collar 89 moved back and forth, but when the member 86 engages either of the notches in the T-members 72 or 73, the one engaged being held against movement, and thus the T-member 79 would not be moved and would be held in position 100 by the spring 94. By the ceasing of movement of the T member 79 the collar 89 will thus be held in either of its two extreme positions according to which of the T members 72 or 73 has been engaged by movement 105 of the member 86.

In order that the movable member 86 may be moved to engage into the notches 84 and 85 of the T members 72 and 73, I have provided a slidable bar 100 having an enlarged 115 frame portion 101 intermediate its ends into which is positioned and secured the upper and lower ends of the member 86. The slidable member 100 has its opposite ends 102 and 103 slidably arranged in bearings 104 and 105 arranged in a rectangular frame 106. Said ends 102 and 103 are arranged so as to protrude slightly beyond the sides of the frame 106. Secured in the frame 106 on the opposite sides of the slidable member 100 are a pair of electric coils 107 and 108, which are arranged for moving a pair of pivoted members 109 and 110 carried by the frame 106 when said coils are energized. The free ends of the pivoted members 109 120

and 110 extend to points adjacent the ends of the slidable member 100 so as to engage said slidable member 100 when the coils are energized for sliding the member 100 which in turn will cause the member 86 to engage in either of the notches 84 or 85 of the T members 72 or 73. The electric coils 107 and 108 each have a wire extending therefrom which is grounded, as at 111, while other wires extend from the opposite ends of said coils, as at 112, to a pair of copper plates 113 and 114 arranged upon an ampere meter 115. The plates 113 and 114 are arranged at certain points so as to be engaged by a movable hand 116 arranged upon the ampere meter upon slight movement of said hand. Extending from the hand of the ampere meter 115 is a wire 117 which has its opposite end connected to the spring support 118 of an overload relay 119, which will close a circuit to the ampere meter from the storage battery 120 when the plunger 121 of the overload relay is moved upwardly, said plunger being moved by an electric coil 122 on the overload relay which is wired to the battery, as at 123, and to a generator 124 which in turn is grounded, as at 125. By having the overload relay adjusted so that the plunger will be moved upwardly to form a contact when the generator charges three amperes the circuit will be closed to the hand so that upon slight movement of the hand a circuit will be closed to either of the electric magnet coils 107 or 108, the ampere meter having connection with the wire 117 so that current will be supplied thereto, while said ampere meter is also grounded, as at 126.

When the hand 116 of the ampere meter moves to a position to either indicate that the battery needs charging or is overcharged, the hand will contact with either one of the copper plates 113 or 114, thus closing a circuit to either of the coils 107 or 108 which will swing either of the levers 109 or 110 on their pivots to slide the member 101 through the bearings 104 and 105 which will cause the member 83 to engage in either of the notches 84 or 85 of the T members 72 or 73. The ampere meter is wired to the battery through the overload relay for receiving its current, the circuit being closed when the generator is in operation, due to the fact that said generator will slide the plunger 121 upwardly to engage the spring contact carried by the contact support 118. The battery is grounded, as at 127, so as to complete the circuit to the ampere meter 115, and the coils 117 and 118.

In operation, when the governor is revolving at a low speed, the clutch is engaged and the power will be transmitted through the train of gears 29, 33—34 and 35, and increase said driven shaft to a higher speed. While revolving at a high speed the gov-

ernor will disengage the clutch and cause the pins 55 to engage the gear 35 and thus have a direct drive.

Should the battery be fully charged the collar 89 would be moved over under the governor arms so as to hold the clutch disengaged and cause a direct drive as shown in Figure 4 of the drawings.

It is to be understood that the form of my invention herewith shown and described is to be taken as a preferred example of the same, and that various changes in the shape, size and arrangement of parts may be resorted to without departing from the spirit of the invention or the scope of the subjoined claims.

What I claim is:—

1. In a device of the character described comprising a drive shaft, a gear mounted loose upon said drive shaft, a clutch for locking said gear upon said shaft, a driven shaft, a gear secured upon said driven shaft, a counter shaft, gears upon said counter shaft meshing with said first mentioned gears, means for operating said clutch according to the revolving speed of said drive shaft, and means for locking said drive and driven shafts together when said clutch is disengaged.

2. In a device of the character described comprising a drive shaft, a gear mounted loose upon said drive shaft, a clutch for locking said gear upon said shaft, a driven shaft, a gear secured upon said driven shaft, a counter shaft, gears upon said counter shaft meshing with said first mentioned gears, a governor for disengaging said clutch when operating at a high rate of speed, and pins for locking said drive and driven shafts together when said clutch is disengaged.

3. In a device of the character described comprising a drive shaft, a gear mounted loose upon said drive shaft, a clutch for locking said gear upon said shaft, a driven shaft, a gear secured upon said driven shaft, a counter shaft, gears upon said counter shaft meshing with said first mentioned gears, a governor for disengaging said clutch when operating at a high rate of speed, pins for locking said drive and driven shafts together when said clutch is disengaged, and means to be operated to hold said clutch disengaged.

4. In a device of the character described comprising a drive shaft, a gear mounted loose upon said drive shaft, a clutch for locking said gear upon said shaft, a driven shaft, a gear secured upon said driven shaft, a counter shaft, gears upon said counter shaft meshing with said first mentioned gears, a governor having arms that open when operating at a high rate of speed for disengaging said clutch, means for locking said drive and driven shafts together when said clutch is disengaged, a slidable collar,

and means adapted to be operated for sliding said collar under said governor arms.

5. In a speed change device, the combination of a drive shaft, a driven shaft, means for increasing the speed of said driven shaft when said drive shaft is rotating at a low rate of speed and to form a direct drive

when said drive shaft rotates at a high rate of speed, and means adapted to be operated for maintaining the direct drive irrespective of the speed of said drive shaft.

In testimony whereof, I have affixed my signature.

CONRAD H. OHLMANSTEK
